UNITED STATES PATENT OFFICE.

AUGIE L. HANSEN, OF EVANSTON, ILLINOIS, ASSIGNOR TO JUSTRITE MANUFACTURING COMPANY, OF CHICAGO, ILLINOIS, A CORPORATION OF ILLINOIS.

IGNITING DEVICE.

1,151,521.

Specification of Letters Patent. Patented Aug. 24, 1915.

Application filed January 20, 1913. Serial No. 743,075.

To all whom it may concern:

Be it known that I, AUGIE L. HANSEN, a citizen of the United States, residing at Evanston, county of Cook, and State of Illinois, have invented a certain new and useful Improvement in Igniting Devices, of which the following is a specification.

My invention is designed to produce a device which may be used by miners using 10 acetylene gas lamps, now so greatly in use in coal mines, such as are described in my Design Patent #42,460, issued May 7, 1912, and is designed to obviate the annoyance caused by the failure of matches to ignite, 15 due to the dampness prevalent in mines.

My invention has for its object to produce a device which will produce a spark which will ignite the gas, and to construct the device so simply, yet strongly, that it 20 will be within the means of the miners.

My means of accomplishing the foregoing may be more readily understood by having reference to the accompanying drawings, which are hereunto annexed and are a part 25 of this specification, in which:

Figure 1 is a sectional elevation of my improved device showing the interior construction. Fig. 2 is a front elevation of the same. Fig. 3 is an enlarged fragmentary detail 30 view showing the arrangement of the friction wheel and sparking material.

As shown in the drawings, 1 is a handle which is formed of tubing and is provided with a pin or pivot 2.

3 is a wheel which is fixedly mounted upon the shaft 2 and has its periphery roughened.

4 is a rod formed of suitable material, such as auermetall, pyrophoric, or any other of the well-known materials employed for 40 this purpose, which will when brought in contact with sharp or roughened points of steel produce a spark. This rod is engaged by an inverted U-shaped member 5 which is slidably mounted in a sleeve 6, the outer 45 end of the U-shaped member being engaged by a hook 7 which is formed on the end of a coil spring 8, the other end being secured to a cap 9 fitted on the lower part of the tube 1. This arrangement serves to produce a 50 constant spring tension upon the rod 4, holding it in engagement with the periphery of the wheel 3.

10 is a lever which projects outwardly from the shaft 2 on which the wheel 3 is 55 mounted. This lever as shown is provided

with a hub 13 which extends laterally along the shaft, the lower part of which is provided with an outwardly projecting lug 14, the latter being provided with a hole 15 to which is secured one end of a coil spring 16, 60 which holds the lug 14 at the lowest point of the circumference of the hub.

The operation of the device is as follows: The operator presses his thumb upon one end of the lever 10 and draws it down. This 65 has the effect of stretching the coil spring 16 so that when the lever is released the spring rotates the wheel 3 very rapidly, its roughened periphery contacting with the end of the rod 4 serving to produce a spark in the 70 usual manner employed by devices of this character.

It will be apparent from the foregoing description that the operating parts of the device are almost entirely inclosed, thus preventing accidental displacement of the operating mechanism, which results in materially reducing the liability of the device to 75 get out of order.

Having described my invention, what I 80 regard as new and desire to secure by Letters Patent is:

1. In a device of the character described, a tubular handle, a shaft mounted in one end of said handle, a wheel fixedly mounted 85 on said shaft, the periphery of which is roughened, a sleeve formed on an upwardly extending portion of the tube, a U-shaped member slidably mounted in said sleeve, a rod of sparking material located in said 90 sleeve intermediate the end of the U-shaped member and the periphery of the wheel, a spring mounted within said tube, one end of which is secured to the upper end of the U-shaped member, the other end being secured to a cap mounted on the lower end of the tube, a lever fixedly attached to said 95 shaft, said lever being provided with a laterally extending hub, an outwardly projecting lug on said hub, which engages one end of a second coil spring mounted inside of the tubular handle, all combined and arranged as and for the purpose set forth, substantially as described.

2. In a device of the character described 105 a tubular handle, a shaft having its ends journaled in the walls of the tube adjacent the one end thereof, a cap closing the other end of said tube, a wheel fixedly mounted on said shaft, the periphery of said wheel 110

being roughened, a U-shaped member, a sleeve in which one end of the U-shaped member slides, a rod of sparking material located in said sleeve intermediate the end 5 of the U-shaped member and the periphery of the wheel, a lever fixedly attached to said shaft, and springs located entirely within said tube, to produce a pressure on said sparking material, and to hold said lever 10 normally longitudinally of said tube.

3. In a device of the character described a tubular handle having a cap closing one end, a sleeve formed from an upwardly extending portion of the tube at its other end, 15 the passage through said sleeve being within the walls of the tube, a shaft having its ends journaled in the walls of the tube adjacent said sleeve, a wheel fixedly mounted on said shaft in line with the opening 20 through said sleeve, the periphery of said

wheel being roughened, a U-shaped member one end of which is slidably mounted in said sleeve, a rod of sparking material slidably located in said sleeve intermediate the end 25 of the U-shaped member and the periphery of the wheel, a lever which projects outwardly from a hub fixedly secured to said shaft, a lug projecting from said hub opposite to the said lever, a coil spring located entirely within said tube one end of which 30 is secured to the said lug, a spring entirely located within said tube adapted to produce a pressure on said sparking material for the purpose set forth substantially as described. 35

In testimony whereof I have signed the foregoing specification.

AUGIE L. HANSEN.
